COUPLING SYSTEM

Nelson P. Case, Bayside, N. Y., assignor to Hazeltine Corporation, a corporation of Delaware

Application June 21, 1935, Serial No. 27,656

12 Claims. (Cl. 178—44)

This invention relates to radio-frequency coupling systems for radio receivers and more particularly to tunable coupling systems for multi-band receivers.

5 The selectivity of a radio receiver is related to the number of tuned signal-selecting circuits employed. It is customary to provide a vacuum tube serving as a radio-frequency amplifier between successive tuned radio-frequency signal-selecting circuits. Thus, when obtaining increased selectivity, it is frequently found that there is also obtained an antenna to detector over-all gain which is greater than is needed or desired. It is therefore desirable to provide, 10 under such conditions, means that will alter the over-all gain without impairment of the selectivity and fidelity of the receiver.

The above problem becomes more acute in multi-band radio receivers, for a general characteristic of such receivers is that the attainable antenna to detector over-all gain is smaller as the band in which the receiver is tunable is higher in the frequency spectrum. As a consequence, in multi-band radio receivers there is the further problem of providing means which compensates for such variations in gain so as to obtain an over-all gain which is more nearly uniform from band to band.

It is an object of this invention to provide a 20 coupling system by means of which the over-all gain of a radio receiver may be altered or controlled in a simple, economical manner without impairment of the selectivity or fidelity of the receiver.

35 It is another object of the invention to provide a coupling system for multi-band radio receivers which is effective automatically to control the over-all gain in accordance with the band in which the receiver is operated, such coupling system being of simple and economical construction and effective without impairment of the selectivity and fidelity of the receiver.

A further object of the invention is the provision of a coupling system employing high inductances and in which the inductance elements may be constructed and mounted in the receiver with ease and economy.

Other objects of this invention will become apparent from the specification taken in conjunction with the accompanying drawing and the appended claims.

The principal field of use of this invention is as a coupling system between successive radio-frequency stages of a radio receiver.

The invention contemplates, for a given band of frequencies, a coupling system comprising a fixed tuned primary circuit and a variably tuned secondary circuit. The primary circuit is preferably tuned to a fixed frequency somewhat below the lowest frequency of the given band, with the secondary circuit tunable over the given band, preferably by a variable condenser. In accordance with this invention, the secondary circuit is non-inductively related to the primary circuit, the coupling between the two circuits being provided by a capacitance of such value that it serves also to align the secondary circuit with one or more other associated tunable circuits. Since, in accordance with the invention, the primary and secondary circuits are non-inductively related, the primary circuit inductance and the secondary circuit inductance may be, and preferably are, mounted independently. This contributes to the simplicity of the receiver construction, for the primary circuit inductance is relatively large and the mounting of it in inductive relation with the secondary circuit inductance involves various mechanical expedients in manufacture and assembly, all of which entail expense. This expense is avoided with this invention.

The invention contemplates, for two or more bands of frequencies, a coupling system for each band similar to that described for one band, with the provision that the coupling capacitances for the several bands progressively increase in value as the respective bands are higher in the frequency spectrum. It is also a provision of the invention that the ratio of the maximum to minimum frequencies in the several bands decrease as the bands are higher in the frequency spectrum.

The single figure of the drawing is a circuit diagram, partly schematic, illustrating an embodiment of the invention as incorporated in a multi-band superheterodyne receiver.

Referring now to the drawing, the multi-band superheterodyne receiver there shown comprises an antenna circuit 10 connected to a radio-frequency selector circuit 11. The selector circuit 11 may be of conventional type, including a plurality of inductances (not shown) of different values, selectively connected by a switching mechanism 12 in circuit with a relatively large variable tuning condenser 13 to form a plurality of closed circuits severally tunable over different bands of signal frequencies. The output of the selector circuit 11 is connected to the signal input circuit of vacuum tube 14, operating as a radio-frequency amplifier.

55

The output circuit of vacuum tube 14 is connected to the input of the multi-band tuned radio-frequency coupling system, generally designated 16. The output circuit of coupling system 16 is connected to the input of an oscillator-modulator 17, which may be of conventional type, including a plurality of inductances (not shown) of different values, selectively connected by a switching mechanism 20 in circuit with a 10 relatively large variable tuning condenser 21 to form oscillation circuits severally tunable over bands of frequencies having a fixed relation to the bands of signal frequencies, so as to produce a constant intermediate or beat frequency in the 15 output of the oscillator-modulator 17. The oscillator-modulator 17 is connected in cascade with an intermediate-frequency amplifier 22, a detector and automatic gain control source 23, an audio-frequency amplifier 24, and a sound reproducer 25. The automatic gain control bias potential may be applied to one or more of the intermediate-frequency amplifier 22, the oscillator-modulator 17 and the radio-frequency amplifier tube 14, as desired. Switch 12 of the 20 radio-frequency selector circuit 11 and switch 20 of the oscillator-modulator 17 are preferably ganged for unicontrol, as indicated by the dotted lines 26. Also ganged with switches 12 and 25 30 are four switches 27, 28, 29, and 30 of the coupling system 16, as will be described hereinafter.

The variable tuning condenser 13 of the radio-frequency selector circuit 11 and the variable condenser 21 of the oscillator-modulator 17 are 35 preferably ganged for unicontrol, as indicated by the dotted lines 33. A variable tuning condenser 34 for coupling system 16, in general similar to variable condensers 13 and 21, is also ganged with these variable condensers, as will 40 be described hereinafter.

40 Considering first the operation of the receiver as a whole, and neglecting for the moment the coupling system 16, per se, the desired received signal wave is selected in selector circuit 11, amplified in tube 14, further selected and transferred by coupling system 16 to the oscillator-modulator 17, where the signal is converted into a signal-modulated intermediate frequency. The signal, as thus converted, is amplified in the intermediate-frequency amplifier 22, converted 45 by detector 23 into the audio frequencies of modulation, amplified in the audio-frequency amplifier 24, and reproduced by the sound reproducer 25.

50 The amplification of the received signal is subject to automatic control by the A. V. C. bias potentials, according to the manner well understood in the art.

The coupling system generally designated 16, 55 comprises a plurality of primary circuits, generally designated 35, a plurality of secondary circuits, generally designated 36, and a plurality of capacitive couplings, generally designated 31, one of each for each of the different bands over which the receiver is tunable. While the circuits 60 35 and 36 have been referred to as "primary" and "secondary" circuits, respectively, for the sake of convenience, it is to be expressly understood that this terminology is not meant to imply inductive coupling therebetween.

70 The primary circuit 35 for the lowest band of frequencies to which the receiver is tunable (customarily the general broadcast band, ranging approximately from 500 to 1500 kilocycles) includes a winding 40a, usually of relatively high

inductance, connected in the plate circuit of vacuum tube 14 when the arm of switch 27 is in engagement with contact 41a, one terminal of winding 40a being effectively grounded through condenser 39. The secondary circuit 36 for such lowest band of frequencies includes a winding 42a, usually of relatively low inductance, non-inductively related to the winding 40a and connected to the signal input circuit 43, 46 of oscillator-modulator 17 through a condenser 45, when 10 the arm of switch 28 is in engagement with contact 44a. The secondary circuit 36 for such lowest band of frequencies also includes the variable tuning condenser 34, one terminal of which is grounded. 15

Primary circuit inductance 40a and secondary circuit inductance 42a being non-inductively related, are conveniently, and preferably, separately mounted. As illustrated, winding 40a is mounted within a grounded shield can 41, and winding 42a is mounted within another grounded shield can 48.

The capacitive coupling 31 for the lowest band of frequencies, comprises a small adjustably-fixed capacitance 37a interconnecting high potential portions of the primary and secondary circuits, preferably the high potential terminals of windings 40a and 42a. 25

The primary circuit 35 for the lowest band of frequencies is preferably fixedly tuned to a frequency somewhat below the lowest frequency of such band by capacitance in shunt with winding 40a. This capacitance may comprise a separate condenser or the inherent capacitance of the primary circuit, such as the output capacitance of the vacuum tube 14, including the capacitance due to the presence of the shield customarily provided around the vacuum tube 14, the capacitance to ground of the primary circuit connections, and the distributed capacitance of the 30 winding 40a. This inherent capacitance of the primary circuit is for convenience designated 51 and represented in the drawing, in dotted lines, as a single equivalent fixed capacitance connected between the plate of vacuum tube 14 and 35 ground. 40

The secondary circuit 36 for the lowest band of frequencies—such circuit including, in series, the winding 42a, variable tuning condenser 34 and fixed condenser 45—is tunable by variable condenser 34 over a band which has a fixed relationship to the tuning bands of the corresponding radio-frequency selector circuit and the corresponding oscillation circuit. Adjustably-fixed condenser 37a is of such value, together with the inherent capacitance 51 of the primary circuit 35, as to align the secondary circuit 36 with the radio-frequency selector circuit 11 and the oscillation circuit of the oscillator-modulator 17 over their respective bands. Such alignment of secondary circuit 36 by adjustably-fixed condenser 37a has its principal effect in the high-frequency portion of such band, similar to the well-known effect of a parallel trimming capacitance. Fixed condenser 45 serves in the conventional manner to align the secondary circuit with the other tunable circuits in the low-frequency portion of such band and also to by-pass radio-frequency currents around the A. V. C. resistors. 50 60 65 70

It will thus be seen that adjustably-fixed condenser 37a serves, for the lowest frequency band over which the receiver is tunable, not only as the coupling means between the primary and secondary circuits 35 and 36 for such band, but also to 75

align the secondary circuit with the other tunable circuits in said receiver.

Furthermore, it will be appreciated that the value of adjustably-fixed condenser 37a ordinarily is relatively small (of the order of 2-10 micro-microfarads) so that the net coupling between the primary and secondary circuits is relatively small. In other words, the energy transfer between primary and secondary circuits 35 and 36 is relatively small, thus providing a coupling system that has an over-all transfer ratio somewhat less than that of conventional coupling systems. At the same time, the progressive decrease in the capacitive reactance of condenser 37a, and the consequent progressive increase in the capacitive coupling between the circuits 35 and 36, as the system is tuned to the higher frequencies of any particular band, compensates for the progressive decrease in the responsiveness of the primary circuit 35, due to that fact that it is permanently tuned somewhat below the band.

Thus, coupling system 16 comprises an inter-stage radio-frequency coupling system constituting a simple, effective and economical gain proportioning or reducing means that does not impair the selectivity or fidelity of the receiver.

For each of the other bands of frequencies to which the receiver is tunable there is a primary circuit inductance 40 mounted within the shield can 47, a secondary circuit inductance 42 mounted within the shield can 48, and an adjustably-fixed capacitance coupling 37. The corresponding elements for the several bands are similarly designated, except that each has a suffix representing the band for which such element is provided. In the embodiment of the invention illustrated, the receiver is tunable over four successive bands, each higher in frequency than the preceding band. For convenience the general broadcast band is herein designated as band *a* and the three other bands, each above the general broadcast band are designated respectively *b*, *c*, and *d*. For each of bands *b*, *c*, and *d* the values of the several elements are such that for the several bands the coupling system functions in a manner similar to that described in detail for band *a*. In this connection, it is to be observed that the absolute value of the inherent capacitance of the primary circuit, represented by fixed condenser 51, is dependent upon the band under consideration, for the capacitance to ground of the primary circuit connections and the distributed capacitance of the shielded primary circuit inductances for the several bands vary to some extent.

Switch 27 in the primary circuits selectively connects in the output circuit of vacuum tube 14 the primary circuit 35 for the band to which the receiver is adjusted for reception. Similarly, switch 29 in the secondary circuits selectively connects in circuit with the input of the oscillator modulator 17 the secondary circuit 36 for the band to which the receiver is adjusted for reception. Switch 28 in the primary circuits selectively short-circuits the primary circuit inductances for all bands below that to which the receiver is adjusted for reception. Similarly, switch 30 in the secondary circuits selectively short-circuits the secondary circuit inductances for all bands below that to which the receiver is adjusted for reception.

In the application of the invention to multi-band receivers, it is preferred to have capacitance couplings 37 of progressively larger value as the bands over which the receiver is tunable are

higher in the frequency spectrum. This results in coupling system 16 having a progressively greater energy transfer in the higher frequency bands than in the lower frequency bands, for, as previously explained, the available over-all gain from antenna to detector in the high-frequency bands is, customarily, less than that in the low-frequency bands.

By virtue of such proportioning of the coupling capacitances 37, the bands in which the receiver is tunable are so determined that the ratios of the maximum to minimum frequencies of the several bands progressively decrease as the bands are higher in the frequency spectrum.

While I have described what I at present consider the preferred embodiment of my invention, it will be obvious to those skilled in the art that various changes and modifications may be made therein without departing from my invention, and I, therefore, aim in the appended claims to cover all such changes and modifications as fall within the true spirit and scope of my invention.

What is claimed is:

1. In a radio receiver including a plurality of vacuum tubes and a circuit tunable over a given band of frequencies, a coupling system for coupling said tubes in cascade comprising; a primary circuit; a secondary circuit in non-inductive relation to said primary circuit and tunable over a band having a fixed relationship to said given band; unicontrol means for simultaneously tuning said tunable circuits over their respective bands; and means for aligning said secondary circuit with said first tunable circuit over said band comprising capacitance connected between said primary and secondary circuits.

2. In a radio receiver including a plurality of vacuum tubes and a circuit tunable over a given band of frequencies, a coupling system for coupling said tubes in cascade comprising; a primary circuit fixedly tuned to a frequency outside said given band; a secondary circuit in non-inductive relation to said primary circuit and tunable over a band having a fixed relationship to said given band; unicontrol means for simultaneously tuning said tunable circuits over their respective bands; and means for aligning said secondary circuit with said first tunable circuit comprising capacitance connected between said primary and secondary circuits.

3. In a radio receiver tunable over a given band of frequencies and including a plurality of vacuum tubes; a first circuit, fixedly tuned to a frequency below said given band, connected to the output of one of said tubes and having a portion thereof effectively grounded; a second circuit, tunable over said given band and non-inductively related to said first circuit, connected to the input of a succeeding one of said tubes and having a portion thereof effectively grounded; a third circuit tunable over a band having a fixed relationship to said given band; and means for aligning said second circuit with said third circuit comprising capacitance coupling high potential portions of said first two circuits.

4. In a radio receiver tunable over a given band of frequencies and including a plurality of vacuum tubes; a first circuit, fixedly tuned to a frequency below said given band, connected to the output of one of said tubes; a second circuit, tunable over said given band and non-inductively related to said first circuit, connected to the input of a succeeding one of said tubes; a third circuit tunable over said given band; and means for aligning said second circuit with said third circuit

circuit comprising capacitance connected between said first circuit and said second circuit.

5. In a radio receiver tunable over a given band of frequencies and including a plurality of vacuum tubes; a first circuit, fixedly tuned to a frequency below said given band, connected to the output of one of said tubes; a second circuit, tunable over said given band and non-inductively related to said first circuit, connected to the 10 input of a succeeding one of said tubes; a third circuit tunable over a band of frequencies differing from the frequencies of said given band by a constant amount; and means for aligning said second circuit with said third circuit comprising capacitance coupling connected between said first circuit and said second circuit.

6. In a radio receiver, a tunable system comprising; a primary circuit including a high inductance winding, said primary circuit having an inherent capacitance to ground permanently 20 tuning said circuit; a secondary circuit including a low inductance winding non-inductively related to said primary circuit and including also a variable tuning condenser, one terminal of 25 which is grounded; and a small adjustably-fixed capacitance interconnecting the high potential portion of said primary circuit with the high potential portion of said secondary circuit, and proportioned to serve, in conjunction with said 30 inherent capacitance effectively in series therewith, as parallel aligning capacitance for said variable tuning condenser.

7. A coupling system for a radio receiver tunable over two or more bands of frequencies, comprising; a primary circuit for each of said bands; means for selectively connecting said primary circuits with the input of said coupling system; a secondary circuit for each of said bands non-inductively related to its respective primary 40 circuit, said secondary circuits being tunable over their respective bands; means selectively connecting said secondary circuits to the output of said coupling system; and a capacitance for each 45 of said bands, each capacitance coupling high potential portions of the primary and secondary circuits of the corresponding band, said capacitances being progressively larger as the respective bands are higher in the frequency spectrum.

8. A coupling system for a radio receiver tunable over two or more bands of frequencies, comprising; a primary circuit for each of said bands fixedly tuned to a frequency below its respective band; means for selectively connecting said primary circuits with the input of said coupling system; a secondary circuit for each of said bands non-inductively related to its respective primary circuit, said secondary circuits being tunable over their respective bands; means selectively connecting said secondary circuits to 50 the output of said coupling system; and a capacitance for each of said bands, each capacitance coupling high potential portions of the primary and secondary circuits of the corresponding band, said capacitances being progressively larger as the respective bands are higher in the frequency spectrum.

9. A coupling system for a radio receiver tunable over two or more bands of frequencies, comprising; a primary circuit, including a high-inductance winding for each of said bands fixedly tuned to a frequency below its respective band; means for selectively connecting said primary circuits with the input of said coupling system; a low inductance winding for each of said bands 70 75 non-inductively related to the inductance of the

respective primary circuit; a variable tuning condenser; means for selectively connecting said low inductance windings with the output of said coupling system and with said variable tuning condenser to form a plurality of secondary circuits non-inductively related to said primary circuits and tunable over their respective bands; and a small fixed capacitance for each of said bands, capacitively coupling the high potential terminal of the primary circuit inductance with a high potential portion of the secondary circuit inductance for the respective bands, said capacitances being progressively larger as the respective bands are higher in the frequency spectrum.

10. In a multi-band radio receiver in which the ratios of the maximum to minimum frequencies in the several bands decrease as the bands are higher in the frequency spectrum, a radio-frequency coupling system comprising; a primary circuit, including a high inductance winding, for each of said bands fixedly tuned to a frequency below its respective band, said primary circuit inductances being of decreasing magnitude as the respective bands are higher in the frequency spectrum; means for selectively connecting said primary circuits with the input of said coupling system; a low inductance winding for each of said bands non-inductively related to the inductance of the respective primary circuits, said inductances being of decreasing magnitude as the respective bands are higher in the frequency spectrum; a variable tuning condenser; means for selectively connecting said low inductances with the output of said coupling system and with said variable tuning condenser to form a plurality of secondary circuits non-inductively related to said primary circuits and tunable over their respective bands; and a small fixed capacitance for each of said bands, capacitively coupling the primary and secondary circuits for the respective bands, said capacitances being progressively larger as the respective bands are higher in the frequency spectrum.

11. In a multi-band radio receiver, a first tunable system selectively tunable over two or more frequency bands and a second tunable system selectively tunable over bands having a fixed relationship with respect to corresponding ones of said first-mentioned bands, said first tunable system comprising; a plurality of primary circuits, one for each of said first-mentioned bands; means for selectively connecting said primary circuits with the input of said coupling system; a plurality of secondary circuits, one for each of said first-mentioned bands, with each of said secondary circuits non-inductively related to said primary circuits, said secondary circuits being tunable over their respective bands; means for selectively connecting said secondary circuits to the output of said coupling system; and means for aligning said secondary circuits for the several first-mentioned bands in the first tunable system with the tunable circuits for the corresponding second-mentioned bands in the second tunable system, comprising a capacitance for each of said first-mentioned bands connected between said primary and secondary circuits for the corresponding band.

12. In a radio receiver having two vacuum tubes in cascade and tunable over two or more bands of frequencies in which the ratios of the maximum to minimum frequencies in the several bands decrease as the bands are higher in the frequency spectrum, a first tunable system serv-

ing as a radio-frequency interstage coupling system between two cascaded vacuum tubes and selectively tunable over said bands, and a second tunable system, including a variable capacitance of relatively large maximum value, selectively tunable over bands having a fixed relationship with respect to corresponding ones of said first-mentioned bands, said first tunable system comprising; a high inductance winding for each of said first-mentioned bands, one terminal of each of said inductances being effectively grounded; means selectively connecting said high inductance windings to the plate of the first of said cascaded vacuum tubes to form input circuits for said first tunable system permanently tuned to frequencies below the minimum frequencies of the respective first-mentioned bands by the inherent capacitances of said primary circuits, a low inductance winding for each of said first-mentioned bands non-inductively related to the primary circuit inductance of the corresponding band; a second variable capacitance similar to said first variable capacitance and actuated con-

jointly therewith and having one terminal thereof grounded; means selectively connecting said low inductance winding with said second variable capacitance to form closed secondary circuits severally tunable over said first-mentioned bands; 5 and a small adjustably-fixed capacitance for each of said first-mentioned bands connecting the high potential terminal of the primary circuit inductance with the high potential terminal of the secondary circuit inductance of the correspond- 10 ing band, said adjustably-fixed capacitance being proportioned to serve, in conjunction with said inherent capacitances effectively in series therewith, as parallel aligning capacitances for 15 said second variable capacitance so that the secondary circuits for the several first-mentioned bands in the first tunable system may be aligned with the tunable circuits for the corresponding second-mentioned bands in the second tunable system, such proportioning also compensating for 20 the decrease in the gain as the bands are higher in the frequency spectrum.

NELSON P. CASE.
